(57) **CLAIM**

The ornamental design for a safety cover for a food grinder, as shown and described.

DESCRIPTION

FIG. 1 is a top perspective view of a safety cover for a food grinder illustrating our new design.

FIG. 2 is a bottom perspective view of the safety cover for a good grinder.

FIG. 3 is a top view of the safety cover for a food grinder.

FIG. 4 is a bottom view of the safety cover for a food grinder.

FIG. 5 is a front elevation view of the safety cover for a food grinder.

FIG. 6 is a rear elevation view of the safety cover for a food grinder.

FIG. 7 is a left side elevation view of the safety cover for a food grinder.

FIG. 8 is a right side elevation view of the safety cover for a food grinder.

FIG. 9 is a top perspective view of the safety cover for a food grinder illustrating an open condition of the safety cover; and,

FIG. 10 is a bottom perspective view of the safety cover for a food grinder illustrating an open condition of the safety cover.

The broken lines in the drawings represent unclaimed environment only and form no part of the claimed design. The dot dash broken lines depict boundaries and form no part of the claimed design.
